(57) **CLAIM**

The ornamental design for a lid for beverage container as shown and described.

DESCRIPTION

FIG. 1 is a top front perspective view of a lid for beverage container, showing our new design.

FIG. 2 is a bottom rear perspective view of the lid for beverage container shown in FIG. 1.

FIG. 3 is a front elevation view of the lid for beverage container shown in FIG. 1.

FIG. 4 is a rear elevation view of the lid for beverage container shown in FIG. 1.

FIG. 5 is a left side elevation view of the lid for beverage container shown in FIG. 1.

FIG. 6 is a right side elevation view of the lid for beverage container shown in FIG. 1.

FIG. 7 is a top plan view of the lid for beverage container shown in FIG. 1; and,

FIG. 8 is a bottom plan view of the lid for beverage container shown in FIG. 1.

The broken lines are shown for the purpose of illustrating both parts of the article, as well as environmental subject matter of an exemplary beverage container. The broken lines form no part of the claimed design.

The exemplary beverage container is shown with a symbolic break in the length. The appearance of any portion between the break lines forms no part of the claimed design.

1 Claim, 7 Drawing Sheets
